DESIGN FOR A PACKAGED SET OF SEAMSTRESS ARTICLES

Eugene D. Pennington, Birmingham, Ala.

Application July 19, 1939, Serial No. 86,085

Term of patent 14 years

To all whom it may concern:

Be it known that I, Eugene D. Pennington, a citizen of the United States of America and residing at Birmingham, in the county of Jefferson and State of Alabama, have invented a new, original, and ornamental Design for a Packaged Set of Seamstress Articles, of which the following is a specification, reference being had to the accompanying drawing, forming a part thereof.

I claim:

The ornamental design for a packaged set of seamstress articles, as shown.

EUGENE D. PENNINGTON.
